METHOD OF TREATING WELLS

Philip J. Lehnhard, Jr., Tulsa, Okla., assignor to
The Dow Chemical Company, Midland, Mich.,
a corporation of Michigan

Application May 2, 1939, Serial No. 271,365

3 Claims (CL 166—21)

The invention relates to the treatment of wells. It more particularly concerns a method of treating wells with fluid agents whereby said agents may be introduced into a selected portion or section of a formation penetrated by the bore of a well.

It is generally highly desirable in treating wells with fluid agents to be able to direct the treating fluid into only a selected section of the formation, 10 for otherwise it may be partially or completely wasted, and in some instances exceedingly deleterious effects may result from the introduction of the treating fluid into the wrong portion of the formation. For example, in treating an oil well to seal or shut off a water-bearing stratum, contiguous an oil-bearing stratum, with a liquid sealing agent of the type which spontaneously 15 solidifies, it is highly desirable to direct the sealing solution into only the water-bearing stratum, since its entry into and solidification in the oil-bearing stratum would result in greatly curtailing, if not entirely stopping, the flow of the desired mineral fluid.

It is the conventional practice to attempt to 20 direct the treating fluid into the desired section of the formation by employing some form of packing device, or by maintaining the treating fluid under a column of an inert liquid, such as, for example, oil. However, neither of these 25 methods give generally satisfactory results as regards ensuring that the treating fluid will be directed into only the selected stratum. For example, packing devices are not generally satisfactory because the contour of the well bore is 30 usually highly irregular and oftentimes ends in a cavity which offers little or no opportunity for a packer to seat properly so as to seal one portion of the well bore from another. On the other hand, attempting to direct a treating fluid into 35 a selected stratum by maintaining it under a column of an inert liquid is not generally satisfactory because a portion of the formation adjacent the column of inert liquid may be porous, allowing 40 fluid to drain thereto, and this in turn alters the level at which the treating fluid enters 45 the formation.

It is, therefore, the principal object of the invention to provide a method of treating wells with fluid reagents whereby positive assurance is 50 had that the fluid enters only a selected section of the formation.

Still other further objects of the invention will appear during the course of the following description.

55 I have found that by introducing the fluid

treating agent into a well through a conduit, the lower open end of which is located in a porous bed formed of granular material filling the well bore adjacent the section of the formation to be treated, while a quantity of a non-penetrating liquid mixture is maintained upon the bed or body of porous material, a fluid treating agent can be readily directed into the selected section of the formation.

The term "non-penetrating liquid mixture", as 10 used herein and in the appended claims, means a liquid mixture comprising a suspension or dispersion of a material in a liquid which prevents the liquid from penetrating porous formations, such as a body of sand, but of sufficient fluidity 15 to be readily introduced into the well bore and removed therefrom.

In the accompanying drawing forming a part 20 of this specification, the single figure is a diagrammatic view in vertical section of a well suitably equipped for carrying out the method of the invention. As shown in the drawing, the upper portion 1 of the well bore is cased with a metal pipe 2, while the lower portion 3 of the well bore penetrates an oil stratum 4 and ends 25 in a water-producing stratum 5. Above the ground level, the well is shown equipped with a casing head 11 through which the tubing 12, provided with cap 18, extends into the well. Pipe 13, controlled by valve 14, communicates with the 30 well bore through the casing head 11, while pipe 15, controlled by valve 16, communicates with the well bore through the tubing 12. The well tubing 12 is shown extending into the well to a point adjacent the water stratum 5, its lower perforate 35 end 17 being located in a mass or body of granular material 6, filling the lower portion of the well bore up to a level 7 adjacent the upper portion of the water-producing stratum 5. The remainder of the lower portion of the well bore 40 above the level 7 is shown filled with a quantity of non-penetrating mixture 8 up to a level 9 adjacent the lower end of the metal casing 2. Exterior of the well tubing, the portion of the well bore cased with metal pipe 2 is filled with a pres- 45 suring fluid 10, such as oil.

The operation of the method will be best understood from a description of a treatment wherein a sealing agent is to be introduced into only the water stratum 5. The lower portion 3 50 of the well bore is filled with a granular material, such as sand, fine gravel, or the like, forming a body 6 thereof, up to a point 7 adjacent the upper level of the stratum to be sealed off. The upper level of the granular material can be read- 55

ily determined, as by means of a measuring line carrying a suitable weight. After the requisite amount of granular material has been located in the lower portion of the bore, a quantity of a 5 non-penetrating liquid mixture is introduced into the well through pipe 13, while valve 14 is maintained in an open position, in an amount sufficient to fill the well bore exterior of the tubing up to a point adjacent the lower end of metal 10 casing 2. Thereafter the sealing agent is introduced into the well through pipe 15, while valve 16 is maintained in an open position, pressure being held upon the non-penetrating liquid mixture, as by means of introducing a volume of oil 15 into the well through pipe 12. The liquid sealing agent is forced out through perforations in the lower end of the well tubing and permeates the porous granular mass 6, as well as the stratum to be sealed, but is prevented from rising in the 20 well bore above the level indicated at 7 by the non-penetrating liquid maintained under pressure upon the top of the porous material. After the desired quantity of sealing agent has been introduced, it may be displaced from the well 25 tubing in any known manner, as by introducing a quantity of oil into the well tubing and applying pressure thereto. After the sealing agent has been allowed time to solidify, the well tubing may be pulled from the well, the non-penetrating 30 liquid mixture removed from the well bore, as by bailing.

It is to be understood, of course, that although it is usually preferable to employ only enough 35 non-penetrating liquid mixture to fill the lower portion of the well bore up to the lower end of the casing, if desired the pressuring liquid used on top of the non-penetrating liquid may be dispensed with and the entire well bore exterior of the tubing filled with the non-penetrating 40 liquid mixture.

If desired, the well tubing may be lowered into the porous mass after it has been properly located in the well bore.

Among the granular materials suitable for use 45 in carrying out the method of the invention are sand, gravel, crushed rock, or the like. It is desirable to employ a material of such size that the void spaces between the particles are not large enough to permit ready penetration of the 50 non-penetrating liquid mixture therewith. If very coarse particles are employed, it is desirable to introduce a quantity of sand or the like on top of the coarse particles to keep the non-penetrating liquid from filtering away through 55 the coarse material.

We have found that suitable non-penetrating liquid mixtures for our purpose consist of aqueous dispersions or solutions of an organic jellifying material. The term "organic jellifying material" as used herein means an organic material capable of being dispersed or dissolved in water to make a mobile liquid mixture, which exhibits jellifying characteristics after a time. 60 The composition and source of suitable materials of this type are set forth in U. S. Patent No. 1,998,756. By mixing between about 0.1 and about 8.0 per cent, and preferably about 1.5 to 4.0 per cent, of such an organic jellifying material with water, a non-penetrating liquid is obtained which will readily flow or can be pumped. 65 Such a mixture will also withstand high pressures without penetrating a porous body of sand. A suitable material of this nature, having non-penetrating characteristics when mixed with 70 75

water, can be prepared from starches such as those of cassava or rice by mixing them with water to form a thin paste, and boiling the mixture until the starch is hydrolyzed. The cooked starch is dried at about 80° C. and the dried material ground, preferably to a fine powder. The powder so produced, when mixed with water in a concentration of from 1-8 per cent by weight, readily forms a substantially non-penetrating liquid mixture. Another liquid mixture having 10 non-penetrating characteristics and of an inorganic type may be prepared by dispersing bentonite in water. By mixing from about 1-5 per cent or more of bentonite in water, a non-penetrating liquid mixture is obtained which 15 may be suitably employed in accordance with the invention.

Although the method is particularly useful in connection with a treatment employing a liquid sealing agent of the type which spontaneously 20 solidifies, such as for example, unpolymerized liquid styrene, unpolymerized liquid vinylidene chloride, and unpolymerized phenol formaldehyde resin-forming liquid, or the like, it may also be employed in carrying out a treatment 25 with other types of chemical sealing agents such as those of the type which react with brines naturally present in the formation to produce sealing deposits, or with a solution introduced for the purpose. The method may also be suitably used to ensure the positive introduction 30 of other treating fluids into only a selected portion of the formation, as for example, acids, paraffin solvents, and the like.

Other modes of applying the principle of my 35 invention may be employed instead of the one explained, change being made as regards the method herein disclosed, provided the step or steps stated by any of the following claims or 40 the equivalent of such stated step or steps be employed.

I therefore particularly point out and distinctly claim as my invention:

1. In a method of treating with a fluid agent 45 a selected section of an earth or rock formation penetrated by the bore of a well, the steps which consist in introducing said fluid agent into the well through a conduit, the lower open end of which is positioned in a bed of granular material located in the well bore adjacent the section to be treated, and maintaining a quantity of non-penetrating liquid mixture on top of the granular material during the introduction of the fluid agent.

2. In a method of treating with a fluid agent 55 a selected section of an earth or rock formation penetrated by the bore of a well, said well being equipped with the usual casing and tubing, the steps which consist in positioning the lower open end of the tubing in the well bore opposite the section to be treated, introducing into the well bore a quantity of granular material in an amount sufficient to fill the annular space between the well bore and the tubing adjacent the section to be treated, introducing into the well bore a quantity of a non-penetrating liquid mixture in an amount sufficient to fill the annular space between the well bore and the tubing up to the lower end of the casing, and thereafter 60 introducing a fluid agent into the well through the tubing and thence into the formation while maintaining pressure upon the non-penetrating liquid mixture in excess of that employed to 65 force the fluid agent into the formation.

- 5 3. In a method of treating with a fluid sealing agent a selected section of an earth or rock formation penetrated by the bore of a well, said well being equipped with the usual casing and tubing, the steps which consist in positioning the lower open end of the tubing in the well bore opposite the section to be treated, introducing into the well bore a quantity of sand in an amount sufficient to fill the well bore exterior of the tubing up to the upper level of the section to be treated, introducing into the well bore a

quantity of non-penetrating liquid mixture in an amount sufficient to fill the well bore exterior of the tubing up to the lower end of the casing, and thereafter introducing the fluid sealing agent into the well through the tubing and thence into the formation while maintaining pressure upon the non-penetrating liquid mixture in excess of that employed to force the sealing agent into the formation.

5
